CLAIM

The ornamental design for the contemporary flat drawer cabinet, as shown and described.

DESCRIPTION

FIG. 1 is a front view of a contemporary flat drawer cabinet;

FIG. 2 is a left side view thereof;

FIG. 3 is a rear view thereof;

FIG. 4 is a right side view thereof;

FIG. 5 is a top view thereof;

FIG. 6 is a bottom view thereof;

FIG. 7 is a top perspective view thereof;

FIG. 8 is an enlarged top view of a drawer face of the contemporary flat drawer cabinet;

FIG. 9 is an enlarged front view thereof; and,

FIG. 10 is another alternate top perspective view of a contemporary flat drawer cabinet.

Any broken lines shown in the Figures are for illustrative purposes only and form no part of the claimed design.
